UNITED STATES PATENT OFFICE.

AUGUST HEYSE, OF TERRE HAUTE, INDIANA.

IMPROVEMENT IN KNOB-LATCHES.

Specification forming part of Letters Patent No. **141,714**, dated August 12, 1873; application filed April 12, 1873.

To all whom it may concern:

Be it known that I, AUGUST HEYSE, of Terre Haute, in the county of Vigo and State of Indiana, have invented a new and Improved Knob-Latch, of which the following is a specification:

In the accompanying drawing, Figure 1 represents a vertical elevation of my knob-latch as placed in the door, and Fig. 2 is a horizontal longitudinal section of the same on the line *c c*, Fig. 1.

Similar letters of reference indicate corresponding parts.

The object of my invention is to furnish an improvement in the class of door-locks having a sliding spindle with wedge-shaped pieces attached to it. The invention consists in the arrangement of guide-pieces in connection with the bolt and spindle, as hereinafter described.

In the drawing, *A* represents the door, into which is fitted suitably the lock-plates *B*, which carry between them the latch-bolt *C*, band-spring *D*, and, transversely, the door-spindle *E*, having knobs *F*, and washers *I*. The plates *B* are connected by screws and supports *a* in suitable manner, and provided with slotted perforations for the passage of door-spindle *E*. The straight piece *b*, guides, in connection with the edge of rectangular piece *d* applied to plate *B*, the bolt *C*, guide-piece *d* embracing also partly knob-spindle *E*. Band-spring *D* is coiled around a stud, *f*, of plate *B*, which is flanged and riveted or

screwed to face-plate *g* of the lock. The latch-bolt *C* consists of three parts: Head *h*, shank *i*, and wedge extension *r*. The head *h* is considerably larger than the shank part, and is acted upon at its rear side by the end of band-spring *D*. The wedge part *k* extends sideways in a right angle from shank *i*, forming, with guide-piece *d*, a square aperture for the knob-spindle *E*. Two wedge-projections, *G*, are placed centrally, but in opposite directions, on spindle *E*, and act from both sides on wedge extension *k* of bolt *C*. The latter is, therefore, pressed back whether the knob is pressed or pulled, opening thereby the door. Spring *D* presses bolt *C* forward again as soon as the knob is released. The whole lock is let into the door, which is provided, as well as side face-plate *e*, with slotted perforations, like plates *B*, being compactly arranged therein, and may be furnished cheaply on account of the simplicity of its construction.

Having thus described my invention, I claim as new and desire to secure by Letters Patent—

The rectangular guide-piece *d*, and the extension piece *K* of the bolt embracing the spindle *E*, and the straight guide-piece *b* in combination therewith, all as shown and described.

AUGUST HEYSE.
